WHEEL COVER

George J. Pyshe, Southfield, Mich., assignor to General Motors Corporation, Detroit, Mich., a corporation of Delaware

Filed Apr. 16, 1963, Ser. No. 74,472

Term of patent 7 years

(Cl. D14—30)

I claim:

The ornamental design for a wheel cover, substantially as shown.
